UNITED STATES PATENT OFFICE.

GEORGE E. RUTLEDGE, OF CHICAGO, ILLINOIS, ASSIGNOR TO VASSAR SWISS UNDER-WEAR COMPANY, OF CHICAGO, ILLINOIS, A CORPORATION.

UNDERGARMENT.

1,266,995.

Specification of Letters Patent. Patented May 21, 1918.

Application filed March 13, 1915. Serial No. 14,206.

To all whom it may concern:

Be it known that I, GEORGE E. RUTLEDGE, citizen of the United States, resident of Chicago, county of Cook, State of Illinois, have 5 invented certain new and useful Improvements in Undergarments, of which the following is a specification.

My invention relates to the union suit type of undergarment made of either elastic 10 or non-elastic material, as preferred.

The object of the invention is to provide elastic ankle extensions designed for use 15 with a garment of non-elastic material, this extension fitting snugly around the ankle and calf of the leg while the upper or drawers portion of the garment is loose.

A further and particular object is to provide improved means for connecting the upper 20 end of the elastic extension to the lower end of the drawers portion.

The invention consists generally in various constructions and combinations, all as hereinafter described and particularly pointed out in the claims.

25 In the accompanying drawings forming part of this specification,

Figure 1 is a rear view of the drawers portion of the garment, showing my invention applied thereto,

30 Figs. 2 and 3 are detail views, illustrating the manner of attaching the extension to the lower end of the drawers leg.

In the drawing, 2 represents the front portion of the garment, having the opening 35 3, and 5 is the upper or shirt portion of the garment. 9 is a band, extending across the back of the garment and stitched at its upper edge to the shirt portion of the garment.

10 and 11 are rear sections of the garment.

40 13 is a middle seam, forming a continuation in the back of the garment of the seam through the crotch and 14 and 15 are leg portions and 16 is a seam intersecting the seam 13 in the closed crotch and uniting the

45 forward and rear leg portions. The section 11 is cut away at 17 and a gore 24 is inserted at this point, stitched at its upper end to the band 9 and at its outer edge to the section 11 and having a tongue 25 at its

50 lower end which extends into the seat opening and is stitched at its end to the seam 16. This tongue serves to hold the outer portion of the drawers and prevents it from gaping. A flap 18 extends across the seat opening

55 and is provided with a band 19 on its loose

edge that is stitched at its lower end to the drawers portion 14 and is adapted to lie vertically thereon over the seam between the section 11 and the gore 24, and a similar band 20 is provided on said flap across the 60 top thereof to fit the band 9 and is secured thereto by the button 23. This is substantially the construction described in my companion application of even date herewith, and I make no claim to the same in this application. 65

At the lower end of the drawers portions I provide elastic extensions 26, preferably of knit fabric secured to the lower ends of the drawers by bands 27. These bands are 70 cut out in circular form, a portion cut off at one end, and the meeting ends lapped by one another, causing the bands to be contracted at their lower edge and expanded at their upper edge, and presenting a flaring effect. 75 The outer lapping end of the band is secured only at the upper edge to the drawers and is therefore free to open up, a gap in the seam of the extension being provided, as indicated at 28, to allow for this opening of 80 the band. Ordinarily, if the seam of the extension was carried to its upper edge and secured to both the top and bottom of the band, the inelastic band would prevent any advantage being taken of the elasticity of 85 the extension but by securing only the upper edge of the band this difficulty is avoided.

The extensions may be made of suitable length and in various ways the details may be modified and still be within the scope of 90 my invention.

I claim as my invention:

1. A union undergarment comprising an upper shirt portion and a lower drawers portion composed of woven material, elastic 95 extensions for the legs of the drawers portion, bands uniting said legs and said elastic extensions, said bands being cut out in circular form and thereby flaring from their lower toward their upper edges, said bands 100 being divided transversely and having one end lapping by the other end with only the upper edges of said lapping ends joined together.

2. A union undergarment comprising an 105 upper shirt portion and a lower drawers portion composed of woven material, elastic extensions for the legs of said drawers portion, inelastic bands uniting said legs and said elastic extensions, each of said exten- 110

sions having a comparatively short slit in its upper portion and one end of each band extending across the slit in the extension and secured to the upper edge of the band 5 on the other side of the slit.

3. An undergarment having inelastic upper leg portions and elastic lower leg portions, a band for securing said portions together, said elastic leg portions having vertical slits therein at their points of connection with said bands and said bands being divided transversely to allow expansion of said elastic portions at their point of junction with said inelastic portions.
- 10 4. A union undergarment comprising an upper shirt portion and a lower drawers portion, elastic extensions for the legs of said drawers portion, a band uniting said drawers portion and said extensions, said 15 bands being divided transversely and having their ends lapped by one another to ex-

25 pand the upper portion of the band and contract the lower portion thereof, one of said lapping ends being secured only at its upper edge, the lower edge being attached to the elastic extension and the seam of said extension having an opening therein to allow for expansion of said extensions.

5. An undergarment having inelastic drawers portions and elastic extensions 30 therefor, and inelastic bands connecting said extensions with said drawers portions, said bands having their ends lapped by one another and one end being secured only at one edge thereof, thereby permitting expansion of said elastic extensions.

In witness whereof, I have hereunto set my hand this 6th day of March, 1915.

GEORGE E. RUTLEDGE.
